UNITED STATES PATENT OFFICE

EVEN J. ROHNE, OF MINNEAPOLIS, MINNESOTA.

ELECTRIC HEATING ELEMENT.

1,133,579.

Specification of Letters Patent. Patented Mar. 30, 1915.

Application filed October 30, 1913. Serial No. 798,203.

To all whom it may concern:

Be it known that I, EVEN J. ROHNE, a citizen of the United States, residing at Minneapolis, in the county of Hennepin and State of Minnesota, have invented certain new and useful Improvements in Electrical Heating Elements; and I do hereby declare the following to be a full, clear, and exact description of the invention, such as will enable others skilled in the art to which it appertains to make and use the same.

My invention has for its object to provide an improved electric element adapted to be used as a heating device, and to such ends, generally stated, the invention consists of the novel devices and combinations of devices hereinafter described and defined in the claim.

In the accompanying drawings which illustrate the invention, like characters indicate like parts throughout the several views.

Referring to the drawings, Figure 1 is a diagrammatic plan view of the improved device; Fig. 2 is a fragmentary view of the fabric body of the pad; Fig. 3 is a view partly in plan and partly in section with some parts broken away, showing plug and switch connections and a fragment of the pad; Fig. 4 is a detail view in plan showing one section of the controlling switch; and Fig. 5 is an enlarged fragment of one of the coils and its core.

The body 1 of the pad, the outline of which is shown by dotted lines in Fig. 1, is a flexible member, the body or main element of which is a coarsely woven fabric consisting of warp threads 1^a, main woof threads 1^b and addition or auxiliary woof threads 4, which latter, in accordance with my invention, serve as cores for coils 2 and 3, and are made from soft pliable non-conducting material, such as asbestos yarn.

The coils 2 and 3 are made from very fine wire and are tightly wound around the soft and flexible non-fusible cores 4, in such a way that they are practically embedded therein, and nearly or quite covered by the fibrous surface of the said cores, (see particularly Fig. 5). In this way, also, the coils are made to take up a great deal of wire with a comparatively short core.

The distinctive feature of this invention is the employment of a pliable insulating core in connection with a wire that is, *per se*, bare, or non-insulated but is spirally wound around the said core and drawn into the

same so that its convolutions are not only held out of contact, but are sunken into the core and protected from contact with externally conducting surfaces.

The numeral 5 indicates an ordinary electric plug adapted to be screwed into an ordinary electric socket. This plug is provided with two lead wires 6 and 7.

The wires 6 and 7 lead to a switch, the body of which is preferably made up of two cap-like members 8 and 9, the latter being swiveled on a tubular hub 10 of the former, and held against axial displacement by a collar 11 on the projecting end of the said hub. Both of the sections 8 and 9 are preferably constructed of wood fiber, vulcanized rubber, or other suitable insulating material. Within the member 8 is an annular core 12 of insulating material, and on which are wound three separated terminal coils 13, 14 and 15 that constitute contact pieces adapted to be engaged by a segmental contact 9^a located within and carried by the cap 9.

The wire 6 from the plug 5 is an insulated wire which extends axially through the switch, without electrical connection therewith, and is connected with one end of the coil 2. The other terminal of the coil 2 is connected by a wire 16 to the contact coil 13. The plug wire 7 is connected to the contact coil 15. One terminal of the coil 3 is connected by a wire 17 to the contact coil 14, and the other terminal of the said coil 3 is connected to the wire 16, all as clearly shown in Fig. 4.

By rotary movement of the cap 9, the segmental contact 9^a may be caused to simultaneously engage the coils 13, 14 and 15, or it may be engaged only with the contacts 14 and 15. When the said contact 9^a is engaged only with the contact coils 14 and 15, the flow of the current will be as follows: through wire 6, heating coil 2, heating coil 3, and wire 17 to contact coil 14, and from thence, through contact 9^a, contact coil 15 and wire 7, back to plug 5. Under these conditions, the current cannot short circuit from heating coil 2 through the wires 16 and coil 13, and hence, must pass through both of the heating coils 2 and 3. Otherwise stated, the two heating coils 2 and 3 are then connected in series so that they afford a rent, and hence, produce a relatively low maximum of resistance to the electric current.

When the contact 9^a is connected to all

three of the contact coils 13, 14 and 15, the flow of current will be as follows: from plug 5 through wire 6, heating coil 2, wire 16, contact coil 13, contact 9^a and wire 7, back 5 to plug 5. It will be noted that at this time the circuit is also closed through coil 3 but that all current which passes through the latter must first pass through the coil 2, so that, in fact, very little current will pass 10 through the said coil 3 and the said coil 3 is practically thrown out of action, because the current taking the path of least resistance, will pass from the coil 2 back through wires 16 and other connections noted. In 15 this adjustment of the switch, a much lower electrical resistance is offered to the current than with the previously noted adjustment, and consequently, more current will flow

with the resulting higher heating efficiency. Obviously, when the contact 9^a is turned out 20 of engagement with the contact coils 13, 14 and 15, or into engagement only with one thereof, no current, whatever, will flow through the heating coils 2 or 3.

What I claim is:

An electrical heating element comprising a core of pliable insulating material, and a wire that is, *per se*, bare but is wound around the said core and drawn completely into the same and thus protected thereby.

In testimony whereof I affix my signature in presence of two witnesses.

EVEN J. ROHNE.
